UNITED STATES PATENT OFFICE.

JOSHUA E. AMBROSE, OF JERSEY CITY, NEW JERSEY.

IMPROVEMENT IN COAL-OIL LAMPS.

Specification forming part of Letters Patent No. 42,455, dated April 26, 1864.

To all whom it may concern:

Be it known that I, JOSHUA E. AMBROSE, of Jersey City, Hudson county, State of New Jersey, have invented, made, and applied to use certain new and useful improvements in the construction and operation of lamps for burning coal, petroleum, and other hydrocarbon oils; and I do declare the following to be a full, clear, and correct description thereof, reference being had to the accompanying drawings, making a part of this specification, and to the letters of reference marked thereon, in which—

Figure 1 is a perspective of my improved lamp; Fig. 2, a sectional view of the same, the globe being removed; Fig. 3, a view of the inner cap used with burner; Fig. 4, a view of the outer cap used with burner.

In the drawings like parts of the invention are designated by the same letters of reference.

The nature of my invention consists in the construction and operation, as hereinafter set forth, of a lamp for the purpose of burning coal, petroleum, and other hydrocarbon oils without the use of a chimney, which lamp shall produce a light of equal brilliancy with that produced by a coal oil lamp employing a chimney.

To enable others skilled in the art to make and use my invention, I will speak of the construction and operation of the same.

A shows a basin, to which the oil-fount B is soldered, which basin A is intended to prevent air entering too suddenly the perforations *a a* in the oil-fount B, and which basin A receives any oil that may leak from the oil-fount B.

B shows the fount for the reception of the oil used, which fount is provided with an outer rim and with the perforations *a a* for the admission of air. This oil-fount B is provided with the tube C, placed within it and extending about half way through the same, which tube C keeps the oil used in a quiet state and prevents the agitation of the same while the lamp is in use. The burner is formed of the shell E, provided with the openings *e e*, the wick-tube F, in which the wick is inserted, the box G, the lever H, provided with the spur-wheels *h h* for raising or lowering the wick, the plate *i*, placed over the upper end of the wick-tube F, which plate *i* is provided with lips for the purpose of bringing a portion of

the air upon either side of the wick-tube F directly at the base of the flame, rendering the flame more white, and which plate is also provided with wings to direct the rest of the air through the slots *f* in the inner cap, L, by which means the flame is widened. The box G is employed to inclose the spur-wheels *h h* and prevent the oil around the spur-wheels *h h* from vaporizing and taking fire. The cover of the box G is formed by the bottom *H²* of the shell E, which bottom *H* is made convex to allow the spur-wheels *h h* to be freely turned within the same.

L shows an inner cap provided with the central slot, *m*, through which the wick projects. The edges of this slot *m* are serrated for the purpose of admitting a draft of air between the wick and the outer edges of the slot. The slot *m* is made narrow to prevent the flame extending below the cap L and burning on the under side. The slot *m* being not large enough to admit sufficient air, the inner cap, L, is also provided with the slots *m² m³* on either side of the slot *m*, intended to admit two currents of air from below into the chamber between the outer and inner caps, thus widening the flame. The inner cap is also perforated, as at *ff*, for the admission of air in smaller currents.

M shows an outer cap placed over the inner cap, L, provided with the central slot, *n*, through which the flame protrudes. This outer cap, M, is perforated, as at *gg*, for the admission of air into the chamber formed between the outer and inner caps. A cone, made in the present instance in two pieces, N and *N²*, is also employed, which cone is placed over the burner and over the oil-fount B, and covers the perforations *aa* in the fount B. The main current of air which passes between the basin A and the rim of the oil-fount B, and enters the perforations *a a* in the oil-fount B, is directed and carried by this cone to the perforations *ee* in the shell E, and passes up on the inside of the burner, through the perforations *f* and slots *m m² m³* of the inner cap, L, to the flame, thus forming what may be termed an "inside draft," while the other portion of the air is carried up by the cone, and is forced through the perforations *gg* of the outer cap, M, into the chamber formed between the outer and inner caps, rendering the combustion more thorough. The upper portion of this cone

terminates between the perforations of the outer cap and the lower edge of the slot in the same. It will be observed that should the cone have its termination below the perforations in the outer cap, the flame would be deadened, and if above the lower edge of the slot in the outer cap the flame would be narrowed, inasmuch as the air would be made to impinge against the edges of the flame. Hence the cone is made to terminate as shown in the present instance, by which the brilliancy of the flame is much increased.

P shows the base of the globe Q, to which it (the glass globe) is attached, and R is the top of the globe Q. The base P is perforated, as at p, to admit a current of air which passes upward to the flame between the cone and the globe of the lamp. Without the presence of this body of air the flame would be narrow and forked. The top R of the globe Q is made long to increase the intensity of the flame, while the globe itself may be made of any desired form, or the interior of the lamp, constructed as just described, may be advantageously employed with the frame-work of an ordinary lantern.

My improved lamp being thus constructed, the operation may be thus described: The fount B is filled with oil, the wick placed within the wick-tube, the burner screwed into the fount B, and the cone placed in position over the fount and burner. The wick is elevated to its proper position above the upper cap, trimmed straight across, lighted, and depressed about midway between the outer

and inner caps. The lamp is then placed within the globe, and there held in any convenient manner. The main current of the air entering the perforations a a is directed by the cone through the perforations in the shell of the burner and through the perforations in the upper cap, thus rendering the combustion perfect. The second current of air entering through the perforations in the base of the globe passes directly to the flame, increasing its size and preventing its "forking." The use of the globe shuts off the cold air, increases the draft, and renders the flame whiter. By the use of the lamp thus constructed, and not employing a chimney, I am enabled to gain all the advantages resulting from the use of a chimney, and at the same time dispense with the expense and trouble of one, and furnish a lamp for public thoroughfares and conveyances where a chimney could not be advantageously employed.

Having thus described my invention, what I claim therein as new, and desire to secure by Letters Patent, is—

In combination with the burner constructed as shown and composed of the parts E, F, G, H, H², L, and M, the use or employment of the cone N and N², fount B, and chimney Q R, for the purpose or purposes herein fully described.

JOSHUA E. AMBROSE.

In presence of—

A. TURNER,
I. PAUGE.
